(57) CLAIM

The ornamental design for a base for a set of false eyelashes, as shown and described.

DESCRIPTION

FIG. 1 is a front, right and top perspective view of first embodiment of a base for a set of false eyelashes, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged partial view of FIG. 4;

FIG. 9 is a front, right and top perspective view of second embodiment of a base for a set of false eyelashes, showing my new design;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom plan view thereof; and,

FIG. 16 is an enlarged partial view of FIG. 12.

The broken lines showing a base for a set of false eyelashes are for the purposes of illustrating environment and forms no part of the claimed design.
